[57] **CLAIM**

An ornamental design for a baby bottle package, as shown and described.

DESCRIPTION

FIG. 1 is perspective view of a baby bottle package showing my new design;

FIG. 2 is a right side elevational view thereof; the left side elevational view being a mirror image thereof;

FIG. 3 is a front elevational view thereof;

FIG. 4 is a rear elevational view thereof;

FIG. 5 is a top plan view thereof; and,

FIG. 6 is a bottom plan view thereof.

The broken line showing of bottle is for illustrative purpose only and forms no part of the claim.

FIG. 2**FIG. 1****FIG. 3****FIG. 4****FIG. 5**

FIG. 6
